United States Patent Office.

D. R. FRASER, OF CHICAGO, ILLINOIS, ASSIGNOR TO HIMSELF
AND P. W. GATES, OF SAME PLACE.

Letters Patent No. 92,599, dated July 13, 1869.

IMPROVEMENT IN BALANCE SLIDE-VALVES FOR STEAM-ENGINES.

The Schedule referred to in these Letters Patent and making part of the same.

To all whom it may concern:

Be it known that I, D. R. FRASER, of Chicago, in the county of Cook, and State of Illinois, have invented a new and improved Self-Adjusting Anti-Friction Slide-Valve; and I do hereby declare that the following is a full, clear, and exact description thereof, reference being had to the accompanying drawings, making part of this specification, in which—

Figure 1, sheet 1, is a section taken longitudinally and vertically through the valve-chest and portions of the valve-supporting devices.

Figure 2, sheet 1, is a top view of the parts, with the back plate of the valve-chest removed.

Figure 3, sheet 2, is a cross-section taken through the valve and valve-chest, in the vertical plane indicated by line $z z$ in fig. 2.

Similar letters of reference indicate corresponding parts in the several figures.

This invention relates to an improvement on the D-slide valves, and is designed to relieve the valve from excessive pressure of steam, and at the same time to suspend it from anti-friction rollers.

I am aware that Letters Patent of the United States have been granted to R. C. Bristol and others for arranging reciprocating slide-valves of the D-form upon anti-friction rollers, with the view of relieving the valve in some degree from undue pressure upon its seat, and, therefore, I do not claim, broadly, this principle or mode of supporting valves.

The nature of my invention consists in devices for suspending a slide-valve from a disk which is pressed upwardly by the action of steam in the steam-chest, in combination with anti-friction rollers, arranged so as to relieve the valve from undue friction at its points of suspension from said disk, as will be hereinafter explained.

To enable others skilled in the art to understand my invention, I will describe its construction and operation.

In the accompanying drawings, I have represented my improvement applied to a steam-chest, which, with the exception of its back, or cover A, may be constructed and arranged in the usual well-known manner.

The cover A is constructed with a central cylindrical elevation, a, rising from it, and receiving within it the cylindrical sleeve D¹ of a disk, D, between which sleeve and this elevation an annular packing-ring, c, is interposed, and capped by a stuffing-box ring, a'. This prevents the escape of steam from the chest, around the sleeve.

The disk D, which is represented in the drawings as circular, is parallel to the valve-seat D, and has a rib, d, depending centrally from it, in a longitudinal direction, which rib has shelves D² D² formed on its opposite sides, as shown in fig. 3.

As the upper face of disk D is exposed to the atmosphere, it is obvious that the internal pressure of steam against its bottom side will tend to force it upwardly against the cover A.

The valve E is of the D-form, and is arranged to slide upon the seat B, so as to allow steam to alternately enter ports b, leading to the cylinder, and exhaust through port b', in the usual well-known manner.

On the back of this D-valve, two parallel jaws, G G, are constructed, which receive between them the inverted T-shaped pendant d D² D², and also anti-friction rollers g' g'.

These rollers g' are arranged between the overhanging lips of the jaws G G and the shelves D² D², so that said overhanging portion will bear upon the rollers, and in this manner suspend the valve E by the said shelves.

The rollers g', on each shelf, are connected by their respective shafts to an oblong frame, g, which frame is free to move, in a direction with its length, between the stops d' d', at the extremities of each shelf D², and those surfaces which impinge against the said rollers are faced with steel, as indicated at e e', in figs. 1 and 3.

F F are valve-rods, applied to valve E in any suitable manner, and carried out through stuffing-boxes, applied to the end of the steam-chest.

It will be seen from the above description that steam, acting upwardly against the disk D, will have a tendency to lift the valve E, by counteracting, to a certain extent, the pressure of steam acting upon the back of the valve. In this way, undue pressure of the valve is prevented.

It will also be seen that the valve is suspended from the said disk D, with anti-friction rollers interposed, so as to afford bearings for the valve, and thereby relieve it of undue friction at its points of suspension.

It will furthermore be seen that the said suspension-disk D is formed on a sleeve, D¹, which rises through the cover A of the valve-chest, and is packed steam-tight, but not held rigidly in place. This arrangement will allow the valve to be self-adjusting, and to compensate for a wearing away of its face and seat.

These features, arranged as I have shown and described, or in any other equivalent manner, enable me to produce an anti-friction, self-adjusting slide-valve, which is free from objections attending other attempts to arrive at the above-named results.

Having described my invention,

What I claim as new, and desire to secure by Letters Patent, is—

1. The self-adjusting device D D², with its other parts, constructed and adapted for sustaining the valve E, in the manner substantially as described.

2. The construction of the valve so that it may be suspended upon rollers arranged upon external flanges D^2 , in the manner substantially described.

3. The combination and arrangement of the anti-friction rollers g' , jaws G , on valve E , shelves D^2 , and disk D , substantially as described.

4. The combination, with the slide-valve E , of the

counterbalancing-device D and anti-friction rollers g' , all constructed and arranged substantially as described.

D. R. FRASER.
